UNITED STATES PATENT OFFICE.

ABRAM S. STAATS AND JOHN ILLINGWORTH, OF NEWARK, NEW JERSEY.

CURB-STOP.

SPECIFICATION forming part of Letters Patent No. 394,733, dated December 18, 1888.

Application filed July 17, 1888. Serial No. 280,175. (No model.)

To all whom it may concern:

Be it known that we, ABRAM S. STAATS and JOHN ILLINGWORTH, citizens of the United States, residing at Newark, in the county of

5 Essex and State of New Jersey, have invented certain new and useful Improvements in Curb-Stops; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to provide a more durable and inexpensive curb-stop; and it consists in the improved curb-stop and in the arrangements and combinations of parts, substantially as will be hereinafter set forth, 20 and finally embodied in the claim.

Referring to the accompanying drawings, in which like letters of reference indicate corresponding parts in each of the several figures, Figure 1 is a side elevation of the improved device. Fig. 2 is a section of the same, 25 taken on line *x*. Fig. 3 is an elevation of a key for turning on and off the water through the supply-pipe. Fig. 4 is a section on line *y*, and Fig. 5 is a detail plan of a cap for covering the upper end of the device.

In said drawings, *a* indicates a stop-cock in a pipe, *b*, leading from the street-main to the house-faucets in the ordinary manner, said cock being of the usual construction, with the exception hereinafter noted, and *b'* indicates 35 a box extending vertically in the ground to the surface thereof, and adapted to allow a key, *c*, to be brought into engagement with said cock, whereby the water passing through the supply-pipe may be "turned off" or "turned on," and thus affect the supply in the house. The said box *b'* is of peculiar construction, whereby it may be built at a reduced cost of construction, and be enabled 40 to withstand the effect of frost, and will also be adapted to prevent the entrance of water &c., at its upper end, which would tend to fill the box, and, freezing, to prevent the insertion of the key to the cock. To this end the base 45 of the box is made of a single casting of metal, *d*, longitudinally slotted as at *e*, to allow the passage of the supply pipe or cock *a* there-

through, and to allow of a longitudinal movement of the box under the effect of the frost, without at the same time moving the supply 55 pipe or cock.

Heretofore in certain cases the stop-cock has been rigidly secured or connected to the box, so that when the box was raised by the frost the pipe or cock was either caused to 60 rise with it, or if the said pipe was firmly held in the ground, to be disconnected therefrom, so as to break the pipe and cause a leakage and entail a very considerable expense for repairing.

65 In the improved device the casting is allowed to slide on the supply pipe or cock. To hold the cock and box in proper relative position, the latter is provided with shoulders *f*, Fig. 2, which engages suitable ways, *f' f'*, 70 formed on the casting. By this construction the cock is also given a bearing on the said casting, so that in turning the spigot or valve there is no danger of breaking the supply-pipe or causing a rupture at the joint between 75 the pipe and the cock should said spigot become corroded and be held very firmly in the cock.

At the bottom of the casting the same is provided with laterally-extending flanges *h h*, 80 which present at the lower extremity of the box a broad bearing to engage the ground and prevent the box from being forced downward therein should the upper end be struck inadvertently or otherwise, and by being thus 85 forced downward breaking the supply pipe or cock.

At the upper end of the casting the same 90 serves as a collar or sleeve, *i*, for a wrought-iron or other pipe, *j*. Said sleeve may be provided with a female thread to receive a male thread on the said pipe *j*; or, and preferably, the said pipe *j* is placed in the mold in the casting operation, and the said casting is cast around said pipe, forming a very permanent 95 and impervious joint, into which no water can penetrate. Shoulders *k k* are formed at or near the union of the two parts, which co-operate with the flanges *h h* in preventing the box from being drawn up out of the 100 ground.

At the upper end of the box the same is provided with a cap, *l*, of metal, and preferably of brass. The said cap being screwed on

the end of the pipe *g*, the same forms an impervious joint at a point which will prevent the water from penetrating to the interior of the box.

5 The top of the cap is formed with suitable means—such as the recesses *m m*—to receive a key or wrench, whereby the said pipe may be readily removed.

The operation of the improved curb-stop 10 and key for turning the spigot is as usual, and particular description thereof is deemed unnecessary.

Having thus described the invention, what we claim as new is—

15 The improved curb-stop herein set forth, combining a casting having a slot, *e*, ways *f'*,

flanges *h*, and a sleeve, *i*, serving as a shoulder, a pipe arranged in said sleeve and extending upward therefrom, and at its upper extremity being threaded and provided with 20 a reciprocally-threaded cap, *l*, and a cock having shoulders adapted to engage the ways and slide thereon, substantially as and for the purposes set forth.

In testimony that we claim the foregoing we 25 have hereunto set our hands this 11th day of July, 1888.

ABRAM S. STAATS.
JOHN ILLINGWORTH.
